UNITED STATES PATENT OFFICE

WILLIAM A. NESTER, OF EAST ST. LOUIS, ILLINOIS, ASSIGNOR TO OBEAR-NESTER GLASS COMPANY, OF ST. LOUIS, MISSOURI, A CORPORATION OF MISSOURI

DESIGN FOR A PRESCRIPTION BOTTLE

Application filed August 26, 1932. Serial No. 44,697. Term of patent 14 years.

To all whom it may concern:

Be it known that I, WILLIAM A. NESTER, a citizen of the United States, residing at East St. Louis, county of St. Clair, Illinois, have invented a new, original, and ornamental Design for a Prescription Bottle, substantially as shown in the accompanying drawing, in which—

Fig. 1 is a plan view of a prescription bottle embodying my new design.

Fig. 2 is a side elevation taken toward the circular side as shown in Fig. 1.

Fig. 3 is a side elevation with the bottle rotated clockwise 90° from the position shown in Fig. 2.

I claim:

The ornamental design for a prescription bottle substantially as shown.

WILLIAM A. NESTER.
